METHOD AND MEANS FOR CONTROLLING THE EXHAUST OF INTERNAL-COMBUSTION ENGINES.

Application filed June 30, 1925. Serial No. 40,658.

This invention relates to a method and means for controlling the exhaust of internal combustion engines and has for its object more particularly the modifying of the exhaust pressures in a manner to contribute to a more efficient and uniform operation of the engine.

It has been ascertained that the exhaust discharge from an explosive engine is not, as is commonly supposed, in the form of a single pressure wave of gradually diminishing intensity particularly when the discharge takes place into a conduit of any appreciable length as is the usual practice. On the contrary, the exhaust discharge is in the form of rapidly oscillating pressures or pulsations, the frequency of which is determined by the form, area and length of the discharge conduit. Since the exhaust discharge results in a wave of alternating high and low pressure and since the frequency of the same is such that several alternations of pressure occur during the comparatively short period of the exhaust port opening, it frequently happens that the dimensions of the exhaust conduit are such as to cause a high pressure period in the wave to coincide with the closing of the exhaust port of the engine. This is more prevalent in exhausts of two cycle engines since the duration of the exhaust port opening period is comparatively short and the exhaust gases are expelled with great suddenness and force. Such a result obviously lessens the power efficiency of an engine since far less scavenging of the cylinder takes place during a period of high pressure in the exhaust conduit than would take place during a period of low pressure.

In order to modify and control this oscillatory tendency of such an exhaust so as to insure that the exhaust port closing will coincide with a low pressure period, I propose to impose a load upon the exhaust discharge in a manner which will rapidly dampen the oscillations without creating back pressure upon the engine, and so designed that the inertia effect of the load thus imposed may be adjusted to bring about a condition of pressure as low and perhaps lower than that of atmosphere at the exhaust port at the time of its closing.

To this end, I provide in the exhaust conduit and at a point closely adjacent to the

exhaust port, an aspirating opening with access through a passageway to the surrounding atmosphere whereby the high velocity exhaust gases passing through the conduit will draw in or suck through said opening a quantity of air in somewhat the same manner as an injector. Such a load upon the high velocity exhaust gases will quickly dampen any pressure oscillations therein, and if the aspirating action is made to take effect through a passageway of proper form and dimensions, the inertia of the body of air therein immediately acted upon will cause a low pressure condition at the exhaust port quickly following the initial high pressure of the discharge, which low pressure condition may be timed to coincide with exhaust port closing. For this purpose, my aspirating opening communicates with a passageway of adjustable length and open to atmosphere at its outer end.

Since it is generally desirable to prevent the escape of the exhaust sound through the aspirating opening, the passageway may conveniently be of tortuous form suited for muffling sound in accordance with well known silencing principles. In other words, by mounting a silencer of suitable design over the aspirating opening, it will be possible both to modify the exhaust pressure wave for contributing to a more efficient operation of the engine as well as to muffle or silence the sound of the exhaust at said point. Of course, only a portion of the exhaust noise will tend to escape at the aspirating opening and if all sound from the exhaust is to be quieted, some silencer of standard design should be connected to the outlet of the main exhaust conduit.

Having described in general the aim and object of the invention, a suitable construction for carrying out the same will now be more particularly described in connection with the accompanying drawings, which show a preferred embodiment thereof.

Fig. 1 is a view in elevation of an internal combustion engine with exhaust discharge conduit leading therefrom showing the principal features of the invention in section;

Fig. 2 is a section through discharge conduit and silencer along line 2—2 of Fig. 1.

Referring more particularly to the drawings, 1 indicates the cylinder block of an in-

ternal combustion engine of any suitable type, which may for example be of the two cycle type having an exhaust port uncovered by a piston. 2 is the base or crank case of 5 said engine. 3 indicates a short length of pipe which functions like an injector nozzle leading from the exhaust port of the engine and extending a short distance into a slightly larger pipe 4, which latter serves as the 10 exhaust conduit for the engine.

The exhaust conduit 4 is preferably secured to the side of the engine as shown, and at a proximate point rearwardly of the front open end of pipe 3 is provided with an aspirating opening 5 which communicates with the inner end of a tortuous or spiral passageway 6 in a silencer, indicated generally at 7. The annular space between pipes 3 and 4 leading backwardly from the front open end 20 of said pipe 3 to the opening 5 is designed so that the high velocity gases issuing from pipe 3 into pipe 4 will cause an aspirating action through opening 5 and passageway 6 of the silencer from the open atmosphere.

25 The silencer 7 in the present embodiment is of the spiral scroll type and comprises header plates 8 and 9 with a spirally arranged partition 10 extending therebetween so as to provide in said silencer the passageway 6, as 30 shown in Fig. 2. The inner end of said passageway 6 coincides with the opening 5 in pipe 4 and the outer end is near the periphery of said silencer at 11 for communication with an annular passage open to the atmosphere at 13 and serving as the inlet for said aspirating passageway 6. The header 8 is slightly larger in diameter than header 9 and extending from one side of header 8 and spaced from the scroll 10 is a cylindrical casing 12 whereby the annular inlet passage 13 for said silencer is provided between said casing and the scroll 10.

In order to vary the inertia effect of the body of air contained in the spiral passageway 6 when acted upon by the injector nozzle 3 and thus insure a condition of low pressure at the exhaust port at the proper time for coinciding with the exhaust port closing, the spiral passageway 6 is made adjustable in length. For this purpose, there is mounted a parti-cylindrical plate 14 upon the outermost portion of the scroll 10 so as to overlap the same as shown in Fig. 2. The member 14 may be moved circularly around the scroll 10 so as to in effect extend the outer end of the same and adjust the length of said passageway 6. When the end 15 of the member 14 is carried to the point 16 on scroll 10, the opening at 11 will be entirely 60 closed and thus access to the atmosphere through opening 5 will be also closed. The member 14 may be given its adjustable movement in any suitable manner and, as shown, there is provided at one side thereof a sup- 65 porting spider frame having a bearing sleeve

17 rotatably mounted on pipe 4 and carrying a gear 18 operable through bevel gear 19 and crank 20. A collar 21 fixed to pipe 4 serves to retain the parts in position. Adjacent the outlet end of the conduit pipe 4 is preferably 70 mounted a silencer 25 of any standard design, whereby the main sound from the exhaust will be muffled or eliminated.

The operation of the device may be described as follows: Upon each opening of 75 the exhaust port of the engine, the exhaust gases will emerge with high velocity from the end of injector nozzle 3 into the discharge conduit 4. This will set up a strong aspirating or sucking action through the 80 opening 5 upon the column of air partially confined within the spiral passageway 6. Much of the energy from the discharge exhaust will thus be expended in setting in motion the column of air in passageway 6 85 and this loss of energy will effectively and quickly dampen the tendency toward oscillatory pressure in the exhaust. The inertia effect of the column of air within the passageway 6 when once started in motion 90 by the aspirating action will react upon the end of nozzle 3 for lowering the pressure thereat and at the exhaust port, immediately after the initial high pressure wave from the exhaust. This condition of low pressure at the exhaust port may be properly timed by varying the inertia effect from the column of air in passageway 6 which is done by adjusting the length of said passageway as described and thus a period of low 100 pressure may be made to coincide with the closing of the exhaust port. By the proper adjustments, the reaction from the inertia effect of the air within passageway 6 may be such as to carry the pressure at the exhaust 105 port even below that of atmosphere as is desirable for the most efficient operation of the engine. In addition to thus modifying the exhaust pressures, the device described will effectively dissipate sound waves and 110 furnish substantially noiseless operation.

It is to be understood that various changes in details and arrangements of the parts as shown may be made without departing from the scope and spirit of the invention as 115 hereinafter claimed.

I claim:

1. The combination with an internal combustion engine of means for rapidly damping pressure pulsations in the explosive discharge of gases through a conduit leading from the exhaust port of said engine, comprising an exhaust conduit having an aspirating opening located closely adjacent said port, a silencer at said opening to prevent the escape of the sound of the exhaust therethrough, said silencer being provided with an adjustable passageway for the passage of air to said opening.

2. The combination with an internal com-

130

- bustion engine of means for rapidly damp-
ing pressure pulsations in the explosive dis-
charge of gases through a conduit leading
from the exhaust port of said engine, com-
5 prising an exhaust conduit having an as-
pirating opening located closely adjacent
said port, an injector nozzle from said port
leading into said exhaust conduit, a silencer
at said opening to prevent the escape of
10 the sound of the exhaust therethrough, said
silencer being provided with a spiral pas-
sageway for the passage of air to said open-
ing, and means for adjusting the length
of said spiral passageway.
- 15 3. The combination with an internal com-
bustion engine having an exhaust port of
means for causing the exhaust discharge
- from said port to produce an aspirating
action comprising an exhaust conduit hav-
ing an aspirating opening located closely 20
adjacent said port, a tortuous passageway
leading from said opening to atmosphere of
sufficient length to substantially muffle the
sound from the exhaust at said opening, an
aspirating nozzle from said exhaust port 25
leading into said exhaust conduit, the out-
let of said nozzle being located in proximity
to said aspirating opening, and means for
adjusting the length of said tortuous pas-
sageway. 30

In testimony whereof I have affixed my
signature.
